(57) **CLAIM**

The ornamental design for display module, as shown and described.

DESCRIPTION

FIG. 1 is a perspective view of a display module according to the present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a detailed view of the area “8” of FIG. 5.

The evenly-spaced broken lines illustrate portions of the display module that form no part of the claimed design. The dash-dot-dot broken lines represent the extents of the enlarged detail view and form no part of the claimed design. All unshaded areas within the evenly-spaced broken lines form no part of the claimed design.
